(57) **CLAIM**

A rear bumper for personal watercraft, as shown and described.

DESCRIPTION

FIG. 1 is a perspective view of a rear bumper for a personal watercraft in accordance with the present invention;

FIG. 2 is a front view thereof;

FIG. 3 is a rear view thereof;

FIG. 4 is a right-side view thereof;

FIG. 5 is a left-side view thereof;

FIG. 6 is a top plain view thereof;

FIG. 7 is a bottom view thereof;

FIG. 8 is a cross sectional view taken through line 8—8 of FIG. 2;

FIG. 9 is a cross sectional view taken through line 9—9 of FIG. 2;

FIG. 10 is a cross sectional view taken through line 10—10 of FIG. 4;

FIG. 11 is a cross sectional view taken through line 11—11 of FIG. 6;

FIG. 12 is a cross sectional view taken through line 12—12 of FIG. 6;

FIG. 13 is a cross sectional view taken through line 13—13 of FIG. 6; and,

FIG. 14 is a referential view showing the article in use on a personal watercraft in accordance with the present invention.

The broken line showing of a personal watercraft is for illustrative purposes only and forms no part of the claimed design.
